ART OF COLORING LEATHER

Filed June 15, 1926

Fig. 1.

UNITED STATES PATENT OFFICE.

PETER A. BLATZ, OF WILMINGTON, DELAWARE.

ART OF COLORING LEATHER.

Application filed June 15, 1926. Serial No. 116,084.

The coloring of hides and skins as now practiced in tanneries, particularly in the coloring of goat and kid skins in the manufacture of glazed leather, comprises drumming such skins in the coloring solution.

In all instances the coloring matter is placed in a suitable drum in the form of a bath; the amount of liquid employed approximately half filling such drum. The skins to be colored are taken from the final tanning treatment, usually chrome tanning, while still wet and are placed in such coloring bath and the drum is rotated until the skins have taken up the desired shade; the time involved depending in some measure upon the weight of the skins, and the color they are to have when the drumming operation in such solution has been completed.

In practice there is a tendency for a number of the skins to turn over and fold or "plait," as it is termed in the industry; the grain side of the skin for some reason not exactly known folding longitudinally and maintaining such condition during the drumming action. This folding action results in improper and incomplete coloring of the skin; the edges receiving a greater proportion of color than the rest of the skin which is quite light in shade, much lighter than the color desired and intended. Skins which act in this manner, while perfectly good leather, are so badly colored as to become "seconds"; available only for trimming parts and not susceptible of use in the manufacture of shoes of the color intended.

The object of my invention is to prevent this plaiting or folding with consequent imperfect coloring, and in coloring these skins, particularly in the manufacture of glazed kid, I fasten the skins together in such manner as to prevent them becoming folded improperly during the drumming in the coloring solution.

In carrying out my invention the skins are secured together unsymmetrically in what may be termed an "unbalanced condition," that is to say a part of the flank of a skin is turned over against the flesh side of the same and secured together in this position. By preference, I secure one of the leg ends to one of the shoulder ends, with the grain side outermost. In fastening the skins in this manner it would appear that the liquid in the drum splashes through the skin; dis tended the same so as to bring the entire grain surface in contact with the coloring

solution in the drum; resulting in perfect coloring throughout the entire area of such grain surface and avoiding the imperfect coloring that takes place when an unconfined or unfastened skin becomes folded with the grain surface in contact with itself in the folded condition.

I have shown in the accompanying drawings, which are largely diagrammatic in character, a skin secured together in the manner which I have found highly satisfactory in practice for maintaining the same in position to secure proper coloring; the grain surface being disposed outermost to insure that the coloring solution will wash such surface of the skin thoroughly and secure the desired coloring effect without danger of improper coloring.

In these drawings:

Figure 1, is a view in plan of a skin as it comes from the tanning bath.

Fig. 2, is a view of the skin fastened together in accordance with my improved method, and

Fig. 3, is a view illustrating the shape the skin is believed to assume during the drumming operation.

In the drawings, 1, represents the body of the skin; the flesh side being indicated at A, and the grain side at B. The leg ends are indicated at 2, and the shoulder ends at 3.

In the drawings, 1 represents the body of my invention, one of the leg ends 2, is connected by suitable means, to one of the shoulder ends 3, and such connection may be effected by means of a rivet 4, or similar fastening, or the extremities of these overlying portions may be sewn together. Any method that will hold portions of the skin together during the drumming treatment in the bath of coloring material may be employed, and the particular fastening means forms no part of my present invention.

The skins fastened together in this unsymmetrical manner are in what may be termed an unbalanced condition; that is to say, the folding is of such a character that portions of the flesh side are disposed at each side of the smaller folded portion of the grain surface of the skin so that, in practice, in the operation of drumming wherein the skins are tumbled about in the coloring solution; being caught up by the wooden pegs on the inner surface of the drum and dropped from such pegs as they pass the highest point of the drum, the liquid will

pass and repass through the skin which will open as the liquid comes into contact with the same; insuring complete submergence in the coloring bath and effecting proper coloring of the grain surface.

I have found in practice that when the skins are fastened together in the manner indicated; that is to say when one of the leg ends, for instance is carried across the 10 skin and fastened to one of the shoulder ends, the skin is prevented from folding together with the grain surface in contact, hence proper coloring of the grain surface can be effected. By preparing the skins in 15 the manner proposed, it is possible to properly color an entire batch of skins, whereas in all former methods where the skins were thrown into the drum in the usual loose and disconnected condition, from two (2) per 20 cent to six (6) per cent of such loose skins fold together longitudinally of the same; the grain side adhering together and maintaining such adherence during the drumming treatment for application of the coloring matter and preventing such grain surface receiving the desired coloring effect.

This condition is especially undesirable when the coloring treatment is intended to impart the lighter shades to skins and where- 30 in it is most desirable that the coloring effect shall be uniform over the entire grain surface. I am unable to say why the adherence of the grain side occurs although it would appear that such surface is slightly sticky 35 or tacky, while the flesh side is quite slippery in the wet condition and during the coloring operation. Whatever the reason, it appears to be a fact that it is the grain side of the skin that adheres together and not the flesh side, when unconfined skins fold together automatically.

While I prefer to fasten the skin together in substantially the manner indicated in Fig. 2, it has been found in practice that the leg 45 end may be fastened to the shoulder end or portion on the opposite side of the skin and that a relatively wide zone of the neck end of the skin, for instance, may be the anchorage for such leg end, so long as such 50 positioning of the skin is unsymmetrical and gives the latter an uneven or unbalanced lap or overlay that will permit the liquid to enter between the plies of the overlapped portion of the skin and distend the same 55 during the drumming operation. The objectionable self-folding of the skins which occurs automatically during a drumming operation is, for some reason yet undetermined, longitudinally of the skin; the fold 60 extending along the backbone of the animal, and the skin overlapping substantially the entire surface of the grain side.

Whatever causes this self-folding, it is 65 highly objectionable. A normal and usual quantity of skins for the drumming opera-

tion in a coloring bath, is from 700 to 800, depending upon the weight of the same, i. e., the thickness of the skins treated, and it can be readily seen that a loss of from fifteen (15) to fifty (50) skins which fold and prevent proper coloring, is a material item. Any means that will avoid the production of this relatively large quantity of improperly colored skins is of great value in the glazed kid industry.

By preparing the skins in accordance with my invention, by fastening portions of the same together in the manner indicated with the grain side outermost, I am able to secure perfect coloring of entire batches; a condition never attained when this coloring operation was carried out in the manner common in the industry before the development of my improved method or process.

While I have referred more particularly in the foregoing description to the coloring of skins which are made into glazed leather, by which is meant kid and goat skins and skins of an allied nature usually employed in the manufacture of footwear, it will be understood that my improved method or process of securing the skins together in a condition whereby they will be prevented from self-folding during the coloring operation, is applicable to leathers of a heavier nature, such as the so-called "side" leathers and the lighter hides; calf skins and the like.

I claim:

1. In the art of coloring leather, the step of 100 fastening the skins together; portions of the skins being overlapped in an uneven or unsymmetrical condition, and then drumming such connected skins in a coloring solution.

2. In the art of coloring leather, the step 105 of fastening the skins together with the grain side outermost; portions of the skins being overlapped in an uneven or unsymmetrical condition, and then drumming such connected skins in a coloring solution.

3. In the art of coloring leather, the step 110 of fastening opposite portions of a skin together; the connected portions of the skins being overlapped in an uneven or unsymmetrical condition, and then drumming such connected skins in a coloring solution.

4. In the art of coloring leather, the step 115 of fastening opposite portions of the skins together with the grain side outermost; the connected portions of the skins being overlapped in an uneven or unsymmetrical condition, and then drumming such connected skins in a coloring solution.

5. In the art of coloring leather, the step 120 of fastening skins together by attaching one of the leg ends to one of the shoulder ends; the skins being overlapped to permit this fastening, and then drumming such connected skins in a coloring solution.

6. In the art of coloring leather, the step 125

of fastening skins together by attaching one of the leg ends to one of the shoulder ends with the grain side outermost; the skins being overlapped to permit this fastening, and then drumming such connected skins in a coloring solution.

7. In the art of coloring leather, the step of fastening a skin together in an uneven or unsymmetrical condition by attaching one of its leg ends to one of its shoulder ends; the skin being overlapped to permit this fastening, and then drumming such connected skins in a coloring solution.

8. In the art of coloring leather, the step of fastening a skin together in an uneven or unsymmetrical condition by attaching one of its leg ends to one of its shoulder ends with the grain side outermost; the skins being overlapped to permit this fastening, and then drumming such connected skin in a coloring solution.

9. In the art of coloring leather, overlapping portions of the skins and fastening them in the overlapped condition by attaching one part of an edge portion of a skin on

one side of the same to another portion of the skin at the opposite edge, and then drumming such connected skins in a coloring solution.

10. In the art of coloring leather, overlapping portions of the skins and fastening them in the overlapped condition by attaching one part of an edge portion of a skin on one side of the same to another portion of the skin at the opposite edge; the overlap being so made so as to be uneven or unsymmetrical so that adjacent to the smaller grain surface section of the overlapped portion there will be portions of the flesh side of the skin, and then drumming such connected skins in a coloring solution.

11. In the art of coloring leather, the method of overlapping the skins in an uneven or unsymmetrical condition, securing them together in such overlapped form, and then drumming such overlapped and fastened skins in a coloring solution.

In witness whereof I have signed this specification.

PETER A. BLATZ.

CERTIFICATE OF CORRECTION.

Patent No. 1,625,842.

Granted April 26, 1927, to

PETER A. BLATZ.

It is hereby certified that error appears in the printed specification of the above numbered patent requiring correction as follows: Page 1, line 88, strike out the words "In the drawings, 1 represents the body of" and insert instead "In the preferred manner of carrying out"; and that the said Letters Patent should be read with this correction therein that the same may conform to the record of the case in the Patent Office.

Signed and sealed this 24th day of May, A. D. 1927.

Seal.

M. J. Moore,
Acting Commissioner of Patents.
